UNITED STATES PATENT OFFICE.

JAMES B. CAROLIN, OF NEWARK, NEW JERSEY, ASSIGNOR TO CITY BUTTON WORKS,
OF NEW YORK, N. Y., A CORPORATION OF NEW YORK.

GARMENT-FASTENING DEVICE.

Application filed January 24, 1923. Serial No. 614,587.

To all whom it may concern:

Be it known that I, JAMES B. CAROLIN, a citizen of the United States, and a resident of the city of Newark, county of Essex, and 5 State of New Jersey, have invented a certain new and useful Improvement in Garment-Fastening Devices, of which the following is a specification.

The object of this invention is to provide a 10 device for use as a fastening means for garments, such as coats, belts, or other articles of wearing apparel, which will be of simple construction and composed of few parts which are readily and easily assembled together to form the complete device.

A further object of this invention is to provide a device of the character mentioned in which the necessity of securing the various parts of the device together by soldering, riveting or the like will be avoided, thus greatly simplifying the manufacture of the device, and consequently the cost of production of the same.

With these objects, and any other objects 25 which may hereinafter appear, in view, I have devised the particular arrangement of parts hereinafter set forth and more particularly pointed out in the claims appended hereto.

Reference is to be had to the accompanying drawing, forming a part hereof, in which—

Figure 1 is a view of the rear of the fastening device;

Figure 2 is a front elevation of the same, with parts being broken away to disclose construction, and

Figure 3 is a sectional view on the line 3—3 of Figure 1, looking in the direction of 40 the arrows.

Throughout the various views of the drawing, similar reference characters designate similar parts.

My invention generally consists of a pair 45 of fastening members, herein shown as button-shaped members, detachably connected by a link. In the accompanying drawing, 1 indicates the cup shaped outer cover of each of the buttons. This outer cover is preferably made of celluloid or some similar substance, or if desired, it may be made of metal. It is provided with a circumferential flange or skirt 2 within which snugly fits a back plate or disc 4. This disc 4 is preferably

held in position frictionally, or by reason of 55 its tight fit within its outer cover 1. It may be held in position by any other desired means, such as by bending over the edge of the skirt 2 of the cover member.

A suitable filler 3 is located intermediate 60 of the cover 1 and back plate 4 to give body to the button and prevent distortion of the outer cover. This filler is made of card board of substantial thickness or of any other light-weight flexible material.

At 5 are shown a number of loops or eyes 65 projecting from the back plate 4 to receive the stitches for attaching the buttons to a garment. These eyes 5 are preferably formed by distorting or forcing outwardly 70 material of the back plate 4.

Adjacent one edge of the back plate 4 I provide a pair of spaced slots 6.

At 7 is shown a plate which is provided 75 with an elongated tongue 9 located between the back plate 4 and the filler 3. This plate 7 has one of its ends terminating in an open hook-shaped member 10 which projects through one of the slots 6 and is located at the back of the plate 4.

On the other button I provide a plate 8 which has a tongue portion 11 similar to the tongue 9, and which extends between the back plate 4 and the filler 3. This plate 8 terminates in a hook-shaped member 12 85 which extends out through the slot 6 to form a loop or eye, and has its end projecting back into the other slot 6 to thus form a closed loop.

At 13 is shown the connecting link, which 90 consists of a flat strip of metal having enlarged ends in which are provided the slots 14 and 15. The loop 12 passes through the slot 14 so that the link is permanently connected to the button provided with the plate 8. The hook 10 on the plate 7 being an open hook, enables the link 13 to be detachably connected to it through the slot 15.

It will be seen from the foregoing that a 95 detachable engagement of the buttons may be had by engaging the slot 15 with the hook 10.

If desired, the outer face of the covers 1 may be suitably ornamented or they may be covered with the material from which 105 the garment to which they are attached is made.

It will be noted that the parts of the de-

vice are readily assembled without the use of solder, rivets or the like so that speed and economy in production is attained.

From the foregoing, it is obvious that my invention is not to be restricted to the exact embodiment shown, but is broad enough to cover all structures coming within the scope of the annexed claims.

What I claim is:—

10. 1. A device of the class described comprising a pair of buttons, each of said buttons having a rear plate and an outer face covering, means on said rear plates for attaching each button to an article, each of said rear plates being provided with an opening adjacent its edge, an elongated plate lying between each rear plate and its face covering and having a portion projecting through said opening and terminating in a hook at the rear of the back plate, and a link attached to the hook on one of the elongated plates and adapted to be detachably engaged with the hook on the other plate to unite the two buttons.
15. 2. A device of the class described comprising a button having an outer covering, a disc forming a back plate for said covering, a filler of flexible material interposed between the back disc and the covering, an opening in the back disc, a plate held between the filler and the back plate, said

plate having a portion projecting through the opening in the back plate and terminating in a hook member, and a link adapted to be received by said hook.

3. A device of the class described comprising a button having a cup-shaped covering member, a back plate frictionally held within the same, a slot in said back plate adjacent its edge, an elongated plate held between said back plate and covering member, said elongated plate extending through said slot and having one of its ends terminating in a hook at the rear of the back plate, said hook being adapted to engage with a portion of another fastening member.

4. A device of the class described comprising a button having an outer covering, a back plate therefor, a member provided with a loop at the rear of the back plate, said back plate being provided with a slot adjacent its edge, said loop member being provided with a tongue portion extending through the slot and frictionally held between the back plate and outer covering and a link held by said loop adapted to detachably engage a fastening member.

Signed at the city of New York, county of and State of New York, this 22d day of January, 1923.

JAMES B. CAROLIN.
